WATER HEATER

Jack E. Moore, Granite Falls, N. C.

Application March 22, 1954, Serial No. 417,615

1 Claim. (Cl. 219—41)

This invention relates to a water heater and particularly to a submersion-type heater for heating water for baptismal pools, or the like.

In the utilization of pools or other vessels for supplying water or other liquid for baptismal or other purposes it is desirable to maintain the water at a particularly pleasant temperature so that the persons being baptised will not be shocked, chilled, or otherwise deleteriously affected by contact with the water.

In the pool heater according to the present invention a terminal box is constructed of water-proof material, such as metal, and a plurality of apertures are provided therein for heating elements of the water-proof type and a water-proof cover is connected on the device. The entire device is then connected to a conduit which is utilized as a support for the box so that the elements may be maintained within the water in a pool.

It is accordingly an object of the invention to provide an improved water heater.

It is a further object of the invention to provide a water-proof heater which may be immersed in the water in a pool.

Other objects and many of the attendant advantages of the present invention will be apparent from the following detailed description taken in conjunction with the accompanying drawing in which:

Figure 1 is an elevation partially in section of a baptismal pool with the water heater installed therein;

Figure 2 is a perspective view of the heating unit; and

Figure 3 is an enlarged sectional elevation through the heating unit taken substantially on the plane indicated by section line 3—3 of Figure 2 and showing the construction and arrangement thereof.

In the exemplary embodiment according to the invention a pool water 10 is maintained in any suitable device such as the tank liner 12 herein shown as supported in the ground 14.

The heating unit is constructed of a terminal box 16 preferably formed from suitable water-proof material, such as the metal box. Preferably the box 16 is constructed as a unit either by forging from a sheet, casting or otherwise.

A plurality of apertures 20 and 22 are provided in the bottom of the box 16 and a plurality of water-proof heating elements 24 are provided with U-shaped construction having ends 26 and 28 extending into the apertures 20 and 22, respectively. The ends 26 and 28 are joined by a plate 30 which is secured to the box 16 by suitable means such as the screw fasteners 32.

2

The heating elements 24 may be of any suitable type, but preferably consist of a resistance heating element embedded in insulating material and encased in a metal tube. The heating element is provided with terminals 34 and 36 which extend outwardly from the ends 26 and 28 for connection to suitable terminals such as the bus bars 40 and 42. Obviously, any desired number of the elements 24 may be provided in the box 16 and the bus bars 40 and 42 will connect similar terminals together so that all of the elements 24 may be connected in parallel. Obviously, the terminals of the various elements could be connected in series circuit relation if such a relationship was desired. The box 16 is provided with a plurality of inturned lugs 44 and a substantially flat cover element 46 is provided with apertures 48 through which extend screw fasteners 50 for engagement in a threaded aperture 52 in the lugs 48.

The cover 46 is usually constructed of water-proof material such as metal, or the like, and a compressible gasket 54 is placed between the edge of the box 16 and the cover 46 and is compressed by the screw fasteners 50 to provide a water-proof seal between the box 16 and the cover 46.

A conduit 60 communicates with the interior of the box 16 preferably by means of an aperture 62 in a boss 64 in the cover 46. A pair of electrical conductors 66 and 68 extend through the conduit 60 into the box 16 and the terminals thereof are connected to the bus bars 40 and 42, respectively to supply electrical energy to the heaters 24.

If desired, a thermostat 70 may be supplied for controlling the flow of electrical energy over the conductors 66 and 68, the conductors 66 and 68 being connected to any suitable source of electrical energy (not shown).

For the purpose of exemplification a particular embodiment of the invention has been shown and described according to the best present understanding thereof. However, and it is apparent that various changes and modifications in construction and arrangement of the parts may be readily resorted to without departing from the true spirit and scope of the invention.

What is claimed as new is as follows:

A water heater for immersion in a water tank comprising an elongated closed water-proof box having a cover provided with a central upstanding conduit and a bottom provided with pairs of openings spaced longitudinally of the box, a plurality of U-shaped water-proof electrical heating elements depending from said bottom with ends secured in water-tight relation in the pairs of openings, and a pair of terminals extending into said box, and a pair of bus bars extending longitudinally in the box and connected respectively to corresponding terminals of the pairs, said bus bars having ends extending upwardly through said conduit for connection to a pair of conductors.
